UNITED STATES PATENT OFFICE.

JULIUS SCHIRRA, OF PITTSBURG, PENNSYLVANIA, ASSIGNOR OF SEVEN-SIXTEENTHS TO PETER WEINKAUF AND ONE-SIXTEENTH TO CHARLES H. MASON, OF PITTSBURG, PENNSYLVANIA.

BUILDING MATERIAL.

No. 926,773.

Specification of Letters Patent.

Patented July 6, 1909.

Application filed April 27, 1908. Serial No. 429,521.

To all whom it may concern:

Be it known that I, JULIUS SCHIRRA, a citizen of the United States, residing at Pittsburgh, in the county of Allegheny and State of Pennsylvania, have invented certain new and useful Improvements in Building Material, of which the following is a specification, reference being had therein to the accompanying drawing.

10 My invention refers to improvements in building construction and relates particularly to means for insertion between portions of a wall or upon the surface thereof for preventing passage or circulation of moisture.

15 The invention consists in layers of suitable material as hereinafter described, arranged for connection or interlocking engagement to make a continuous construction, and having qualities of flexibility, impenetrability of 20 moisture and bonding efficiency for engagement with mortar, plaster, etc.

Ordinarily in laying the courses of brick on the foundation walls, masons employ layers of slate for the purpose of preventing 25 the passage of moisture, but as is well known the slate is easily cracked, due to the hard opposing surfaces and pressure, thereby largely destroying its usefulness for the purpose intended.

30 In the drawings illustrating the invention Figure 1 is a view in elevation of a portion of a stone or brick wall provided with my invention. Fig. 2 is a vertical sectional view indicated by the line II. II. of Fig. 1. Fig. 3 is a detail view in perspective of one of the 35 sections of material. Fig. 4 is an enlarged sectional detail view illustrating the construction at the joined end. Fig. 5 is a perspective detail view showing a modified construction. Fig. 6 is a similar view illustrating 40 the female edge of one of said sections. Fig. 7 is a sectional view enlarged indicated by the line VII. VII. of Fig. 5.

In carrying out my invention I provide 45 sections or layers 2 composed of paper or similar material of sufficient thickness, flexibility, and toughness to give a good body of the necessary strength, both edges of which at opposite sides are corrugated as indicated 50 at 3, while the intervening edges at right angles to said edges are pressed by suitable dies so as to reduce the normal thickness of the paper to about one-half, as indicated at 4, 4. It will be observed that the depressions resulting 55 from such operation are located at

opposite portions of the flat surfaces whereby to interfit with the next adjacent section, as fully indicated in Fig. 1 to provide a flush continuation of both faces when said sections are incorporated together in a wall, although the depressions may be on the same side and the layers laid alternately. The corrugated edges 3 are designed to project to within a short distance of the faces of the wall at one or both sides and to provide a bonding attachment for the mortar which is filled into the crevices, said corrugations being conveniently made by crimping the edges between suitable rolls or other device. When thus prepared the sections 2 are entirely covered on both sides and over their entire outer portions with a suitable surfacing material for the purpose of providing an attaching or cementing covering for an outer coating of sand. I have secured good results with a mixture of Keene's cement and paint of any suitable kind, which mixture will form a soft putty-like substance which will closely adhere to the paper and will have great retaining capacity as a cement. Such substance is indicated at 5 in Fig. 4. Over the paper as thus prepared I then sprinkle sand of any suitable kind, preferably sharp white river sand, which becomes tightly incorporated with the coating 5 and when the said coating dries the sand will be firmly incorporated with it and will provide a strong rough surface with which the mortar will become closely bonded when applied. In using the material as thus prepared, continuous layers are laid between courses of stone and brick as indicated in Figs. 1 and 2 or between the adjacent brick courses or stone courses, being laid in mortar, and when the superimposed layer of mortar and the next course of brick is laid thereon, the entire structure will be pressed closely together and my improved material will thus be rigidly incorporated as a permanent portion of the wall.

In the modified construction shown in Figs. 5, 6 and 7, the sections 2' are preferably formed of three separate layers of paper, the middle layer being off-set at one side and end as clearly shown, so as to provide a projecting tongue 6 along said side and end, and a corresponding receiving groove 7 along the other side and end for the reception of the corresponding middle section of the adjacent piece, in the well known manner of a tongue-

- and-groove joint. Such form is particularly adapted as a wall cover and it may be conveniently and efficiently used by tacking upon any surface, wooden or otherwise, for the same general object, to wit, for preventing the passage of moisture and also for providing a good bonding surface for retention for the mortar or other wall-surfacing material.
- 10 By reason of its character, the sections may be readily pierced by nails or tacks and will be rigidly held in place thereby on any surface permitting such method of attachment.
- 15 A further use of the invention is with slate or other roofs, the sections being laid upon the boards of the roof in the same general manner as ordinary paper is laid, providing a continuous intervening layer between the supporting structure and the upper layer or layers of slate, etc.
- Various other uses may be made of the invention in the building arts as may be suggested to the user, the advantages of flexibility and resistance to moisture constituting its chief merits.
- 15 The invention is very useful and econom-

ical, it may be made in various sizes or proportions or changed in different details of construction or treatment by the skilled mechanic, but all such changes are to be considered as within the scope of the following claims.

What I claim is:

1. Building material consisting of interfitting sections of flexible paper provided with a corrugated edge and transverse compressed edges and having a covering of cementitious substances and an outer coating of sand or the like, substantially as set forth.

2. As an improved article of manufacture, a layer of flexible paper having a covering consisting of a mixture of cement and paint and an outer coating of sand impregnated therein, and provided with flattened edge portions of reduced thickness, and intervening corrugated edges, substantially as set forth.

In testimony whereof I affix my signature in presence of two witnesses.

JULIUS SCHIRRA.
